UNITED STATES PATENT OFFICE.

WILLIAM JOSEPH HART, OF ST. JOSEPH, MICHIGAN.

DIRECTION SIGNAL FOR VEHICLES.

Application filed July 17, 1922. Serial No. 575,503.

To all whom it may concern:

Be it known that I, WILLIAM J. HART, a citizen of the United States, residing at St. Joseph, in the county of Berrien and State 5 of Michigan, have invented certain new and useful Improvements in Direction Signals for Vehicles, of which the following is a specification.

My invention relates to devices for indicating upon a motor vehicle the direction in which said vehicle is to be steered and thereby give notice to motorists approaching from either direction of the intention to stop or to steer to either side so that collisions 10 and other accidents may be avoided. My invention seeks to provide a device for the stated purpose which may be easily read by approaching motorists either in daylight or at night, and also seeks to provide a device 15 which may be easily controlled and accurately set by the occupant of the vehicle equipped with the device. Incidental objects of the invention will appear in the course of the following description, and the 20 invention resides in certain novel features which will be particularly pointed out in the claims following the description.

In the accompanying drawings—

Figure 1 is a side elevation, partly broken 25 away, of an automobile equipped with my invention;

Fig. 2 is an enlarged sectional elevation of a portion of the vehicle showing the means for setting the signal;

Fig. 3 is an end elevation of the signal;

Fig. 4 is a view of the same, partly in side elevation and partly in longitudinal vertical section on the line 4—4 of Fig. 3;

Fig. 5 is a detail elevation of the stop 30 rack;

Fig. 6 is an elevation of the display dial and a cover plate employed in connection therewith;

Fig. 7 is a detail sectional elevation of the 35 means for operating the dial;

Fig. 8 is an elevation of the signal as applied to the headlight of an automobile;

Fig. 9 is a longitudinal section of the same, and

Fig. 10 is a detail elevation of a slight 40 modification.

The automobile 1 may be of any well-known or preferred type and is equipped in

the usual manner with a headlight 2 and a taillight 3, a signal 4 embodying my invention being mounted in connection with the headlight and also in connection with the taillight.

The signal or direction indicator comprises a preferably circular casing having 45 an opening, indicated at 5, through its lower portion whereby light from the headlight 2 or from the taillight 3 may pass into the casing when it is desired to illuminate the same. The casing may be of any preferred construction and is equipped at its open or display side with a pane 6 of glass or other transparent material which is colored throughout the greater portion of its area but is provided with a clear space indicated at 7. In the particular embodiment of the invention illustrated in the accompanying drawings, this space 7 is one-fourth of the area of the entire pane and is utilized as a display space through which the desired signal may be read. A shaft 8 is rotatably mounted within the casing, the said shaft being mounted in suitable bearings provided therefor and upon the end of the said shaft is secured a pinion 9 which is engaged by a rack 10 for setting the signal. A partition 11 is preferably provided within the casing, and, in rear of the partition, a reflector 12 of any preferred form is disposed concentrically about the shaft. A box 80 is secured upon the front side of the partition to guide and support the rack 10 and house the same and the pinion 9. The bearings for the front end of the shaft 8 are provided by the partition and the box while 85 the rear end of the shaft is journaled in a bearing frame 81 secured within the casing in juxtaposition to the pane 6. As shown most clearly by the dotted lines in Fig. 8, the bearing 81 is Y-shaped or three-armed 90 whereby it may be so disposed as not to obstruct the display space 7, and it may be here noted that the display space is at the top of the signal mounted upon the taillight and at the bottom of the signal mounted 95 upon the headlight. It will, of course, be understood that in the taillight signal, the bearing frame 81 is at the rear end of the casing, whereas in the headlight signal it is at the front end of the casing. In rear of 100 the reflector, a signal or display disk 13 is

secured upon the shaft, and in rear of the signal disk is a cover plate 16 which is loose upon the shaft between a stop collar 14 and the bearing frame 81, and, in its normal position, disposes a triangular plate or cover 17 over the display space 7, while, depending from the shaft, the said cover plate presents an arm 18 having an arcuate rearwardly extending shield 19 at its lower end, 10 said shield 19 being of sufficient area to extend over the entire area of the opening 5 and thereby prevent the entrance of light into the casing. At one side of the arm 18 is a lug 20, and projecting from the signal 15 plate or dial 13 is a pin 21 which is disposed in the path of the said lug 20 and may be engaged thereby. A spring 15 is coiled around the shaft 8 between the cover plate and the bearing frame and has its ends secured respectively to said frame and the cover plate so that it tends constantly to turn the cover plate about the shaft 8 and thus holds the lug 20 against the pin 21. When the signal disk is rotated, therefore, 20 the cover plate will follow the movement until it has made a quarter turn at which time its movement will be checked by a shoulder 82 at one corner of the screen portion 17 thereof coming into contact with a 25 stop lug 83 on the casing. Return movement of the signal disk will eventually again engage the pin 21 with the lug 20, whereupon the continued movement of the disk will return the parts to normal position.

30 35 The taillight 3 is of the usual construction having a glazed opening 22 in its lower side through which light may pass to illuminate the license plate, indicated at 23, and being further provided with a glazed opening 24 in its upper side which is arranged in alinement with the opening 5 of the signal casing so that the light from the lamp may pass into the signal casing when illumination of the latter is desired. In order to 40 maintain the proper relation of the signal casing and the lamp, I preferably provide the signal casing with a foot or other support 25 which has an arcuate lower edge, as indicated at 26, whereby it may extend over 45 the lamp and support the casing thereon. The said foot may be brazed or otherwise rigidly secured to the casing of the lamp.

50 Referring more particularly to Fig. 6, it will be noted that the dial or display plate 13 has upon its face four direction-indicating legends, to wit: "Stop", "Slow", "Turn" associated with an arrow 27 pointing in one direction, and "Turn" associated with an arrow 28 pointing in the opposite direction, 55 the signal "Stop" being normally at the top of the dial and covered by the triangular head or screen portion 17 of the plate 16. The different legends may have distinctive colorings and they may be merely painted or 60 otherwise produced upon a plate of glass

or other transparent material, or they may be cut in stencil form in a metal disk and then covered with any suitable properly colored material, all of these suggested constructions being well-known. If it be intended to stop the vehicle, the controlling mechanism is set in the stop position and the rack 10 is thereby actuated so that the shaft 8 will be rotated in the direction indicated by the arrow in Fig. 6. The pin 75 21 thereupon tends to move away from the lug 20 but the spring 15, as above described, causes the cover plate to follow the movement of the disk until it has made a quarter turn so that the display space 7 will be uncovered. The disk, however, continues its movement and at the end of a complete rotation will show the word "Stop" through the display space. Obviously, rotation of less extent will bring any one of the other legends into display position as may be desired. Of course, the legends may be arranged in any desired order, but I believe the order illustrated will be generally preferred as the most frequently needed signal "Slow" will be displayed with only a quarter revolution while the full rotation is required for the least frequently needed signal. In daylight, the lamp 3 or 2, as the case may be, will not be burning and, therefore, the interior of the signal casing will not be illuminated, except to such extent as daylight may enter the same. The uncovering of the dial, however, by the movement of the cover plate will cause the desired signal to be displayed sharply and in such a manner as to immediately attract the attention of approaching motorists. When traveling at night, however, the shield or screen 19 will effectually prevent the entrance of light from the lamp into the signal casing so that the signal will be dark and will not be conspicuously noticeable, but when it is desired to display a signal, the movement of the cover plate carrying the shield or screen 19 from over the opening 5 will effect a sudden and complete illumination of the signal which will immediately attract the attention of an approaching motorist so that he will be positively notified of the intention to stop, turn or slow down. In both day and night travel, no signal is displayed when traveling straight ahead and the change of conditions caused by shifting of the signal disk is, therefore, 100 sure to attract attention which is the ultimate result sought. When the signal is applied to the rear end of the vehicle and arranged in connection with the taillight, the rack 10 will move vertically, but when the device is applied to a headlight, the rack 10 will be more conveniently arranged to operate horizontally, as shown clearly in Figs. 8 and 9, and the display space 7 will be arranged at the bottom of the signal casing in- 105 110 115 120 125 130

stead of at the top thereof, as clearly shown. Moreover, when the device is arranged in connection with the taillight, the signal casing will be arranged directly over the tail-light, as shown clearly in Fig. 4, but when arranged in connection with the headlight, the signal casing will be placed in front of the headlight and at the upper portion thereof, as shown in Figs. 8 and 9, so that some 10 of the forwardly projecting light rays will be intercepted and caused to pass into the signal casing.

Referring particularly to Figs. 8 and 9, it will be noted that when applied to the 15 headlight, the signal casing is arranged so as to project in front of the upper portion of the headlight and the opening 5 is formed in the rear wall of the casing. The partition 11 may be omitted and the box 80 arranged 20 exteriorly to the casing. The shield 85, carried by the cover plate is in the form of a trough or cup to pass around the signal plate and cover the opening 5. The light entering the casing from the headlight will be in 25 line with the display area 7 but a reflector 86 conforming to the circumferential wall of the casing may be fitted in the bottom thereof to aid in the illumination of the interior of the casing.

Various means may be provided for controlling and setting the signal, and I have 30 illustrated what I now believe to be the best means for that purpose. The illustrated controlling and setting mechanism includes 35 a rack 29 which is shown as secured upon the instrument board 30, but it may be mounted upon the steering column 31 or otherwise supported in a position adjacent the chauffeur's seat. This rack 29 has upon 40 its face notches or other holding elements, indicated at 32, to be engaged by a dog 33 upon the setting hand lever 34 so as to hold the signal in any set position. The hand lever 34 is also equipped with a pointer 35 45 which acts in conjunction with legends 36 corresponding to the legends upon the dial 13 so that, when the pointer 35 is over any one of the said legends 36, the same legend will be displayed by the signal. The lever 50 or handle 34 is fulcrumed at 37 concentric with the rack 29 and has a depending crank 38. A pitman 39 is pivoted to the free end of this crank and extends forwardly therefrom within a guiding support 40 which is 55 shown as projecting rearwardly from the dash 41 of the vehicle. The front end of this pitman may be connected in any convenient manner with the outer end of the rack 10, and I have found it satisfactory to use a 60 flexible rod, indicated at 42, consisting of wires wrapped within a stout coiled wire casing. This particular connecting medium is well-known and any equivalent of the same may be employed. In order that the 65 operation of the controlling and setting

mechanism may not be dependent upon the use of the hand lever 34, I provide a rock shaft 43 upon the dash 41 and this rock shaft is equipped with upstanding cranks 44 and 45, the crank 45 being connected by 70 a link 46 with the pitman 39 so that any movement of the rock shaft will be transmitted to the pitman, it being noted that the link 46 is provided with a loop or eye 47 at its rear end freely encircling the pitman and 75 adapted to abut a stop 48 on the pitman. The crank 45 is rigid with a downwardly extending crank 49 and the said crank 49 is connected by a link 50 with a slide 51 mounted upon the foot board 52 of the 80 vehicle in position to be engaged by an offset 53 upon the foot brake pedal 54. The crank 44 is connected by a link 55 with a bell crank 56 mounted upon the emergency brake lever 57. It will thus be seen that, 85 should the chauffeur, in an emergency, apply the brakes and forget to set the signal through the use of the hand lever 34, the application of the brakes will automatically 90 effect a setting of the signal so that other motorists will be enabled to avoid a collision. It will, of course, be readily understood that the controlling mechanism may be arranged to be actuated only upon the 95 operation of the emergency brake lever or only upon and whenever the foot brake pedal is operated, such result being attained by merely omitting the other parts of the described mechanism, but I prefer to provide all the described parts upon the vehicle 100 so as to more effectually guard against accidents.

The pane 6 is, as has been stated, provided with a clear space through which the signals are to be read but the remaining portion of the pane is not opaque, it being the intention to color the remaining portion of the pane so that it may transmit light and permit approaching motorists to notice the 105 location of the signal, and the display case 110 7 may be simply an uncolored area of the pane. Preferably, the translucent portion of the pane will be colored red as such color is generally used and is always effective in attracting attention. In Fig. 10, I have 115 illustrated another attention-attracting device which may be employed in conjunction with the previously described elements. This device consists of a plate 58 having an arcuate formation so that it may fit within 120 the cap of the casing 4 over the translucent portion of the cover or pane 6 and is preferably of metal having letters cut out therein so as to display such a legend as "Watch 125 this signal," indicated at 59. At the center of the inner edge of this plate is an arrow 130 or finger 60 which points directly to the display space 7 so that attention will be directed to the essential point of the signal at all times.

My improved signal is obviously simple in the construction and arrangement of its parts and may be readily applied to any vehicle now in use or to be hereafter produced.

Having thus described the invention, what is claimed as new is:

1. A direction signal comprising a casing having a fixed display area at one end, a dial mounted within the casing and bearing legends to be displayed singly through said area, means for shifting the dial to bring a selected legend to the display area, a cover normally closing the said display area, and means for shifting said cover whereby to permit reading of that legend upon the dial which is at the display area.

2. A direction signal comprising a casing having a fixed display area at one end, a legend-bearing dial mounted within the casing, a cover normally closing the display area of the casing, means for shifting the dial to bring a desired legend into view at the display area, and co-operating means on the dial and the cover whereby initial movement of the dial will move the cover from over the display space.

3. A direction signal comprising a casing having a fixed display area at one end, a legend-bearing dial arranged within the casing a pin projecting from said dial, a cover plate normally closing the display area of the casing and having a lug on one side adapted to engage the pin projecting from the dial, means for shifting the dial to bring a selected legend to the display area, means for holding the lug on the cover plate against the pin on the dial whereby the plate will follow the movement of the dial, and means for limiting the movement of the cover plate whereby to release said pin from said lug.

4. A direction signal comprising a casing having an opening at its bottom to admit light thereinto and being further provided with a display area at one end, a legend-bearing dial within the casing, a cover plate normally closing the display area in the casing, a screen carried by said cover plate normally covering the opening at the bottom of the casing, and means for shifting said cover plate whereby to permit illumination

of the casing and reading of a legend upon the dial.

5. The combination of a casing, a legend-bearing dial therein, a shaft disposed within the casing and carrying said dial, a pitman mounted for reciprocation at a point remote from the signal casing, a rock shaft connected with said pitman, flexible connections between said pitman and the shaft within the signal casing, a second rock shaft, a crank on the second shaft, a link extending from said crank and loosely encircling the pitman, means for actuating the second rock shaft, and an abutment on the pitman whereby the pitman may be actuated by the first-mentioned rock shaft without causing movement of the second rock shaft and movement of the second rock shaft will cause the link to engage abutment and actuate the pitman.

6. A direction signal comprising a casing having a display area and a light-admitting opening, a signal dial within the casing, means for shifting the dial, a cover member within the casing constructed to close the display area and the light-admitting opening, and means whereby during a portion of the setting movement of the dial said cover member will be moved to open the display area and the light-admitting opening and during a portion of the return movement of the dial will be restored to normal.

7. A direction signal comprising a casing having a fixed display area at one end, a dial within the casing bearing legends to be viewed at the display area, means for shifting the dial to bring a selected legend to the display area, a cover normally extending over the display area to prevent the reading of a legend, means tending constantly to move the cover in one direction, means on the cover and casing to limit movement of the cover in the one direction, and a member on the dial projecting into the path of the cover to hold the same in normal position and permit its movement in the one direction upon movement of the dial in the same direction and restore the cover to normal upon return movement of the dial.

In testimony whereof I affix my signature.

WILLIAM JOSEPH HART. [L. s.]
